Armin G. Brendel, Suffern, N. Y., assignor to American Cyanamid Company, New York, N. Y., a corporation of Maine

Original application July 21, 1949, Serial No. 105,943, now Patent No. 2,644,516, dated July 7, 1953. Divided and this application January 27, 1953, Serial No. 333,550

1 Claim. (Cl. 159—4)

This invention relates to a spray machine for use in spray driers employed for drying solid material dissolved or suspended in a liquid. Although not limited thereto, the apparatus of the invention is particularly well adapted for the spray drying of slurries containing gelatinous silica, including silica-alumina, silica-magnesia and silica-alumina-magnesia compositions for use in the catalytic cracking of petroleum hydrocarbons. For this reason the invention will be described in detail with particular reference to the spray drying of this class of materials; it being understood, however, that slurries or solutions of other solid or semi-solid material may be dried therewith.

In the spray drying of silica slurries for the production of microspheroidal cracking catalysts a two-phase slurry consisting of water containing small globules of hydrated silica, silica-alumina, silica-magnesia and the like is dispersed into a current of hot gases in a spray drying chamber. Usually the slurry is dispersed by discharging it onto a rapidly rotating motor-driven vane spray wheel mounted in the top of the drying chamber. A current of hot gases, such as hot products of combustion, is admitted tangentially around the spray wheel and forms a rotating vortex into which the spray of silica slurry is projected by centrifugal force. My present invention provides an improved air- and water-cooled motor and an improved non-clogging distributor for supplying the material to be dried to the spray wheel as will hereinafter be more fully pointed out and defined by the appended claim.

The invention will be further described with reference to the specific embodiment thereof shown in the attached drawings in which:

Fig. 1 is a vertical section through a furnace and top portion of a spray drier with parts broken away.

Fig. 2 is a vertical section through the motor and cooling jacket assembly.

Fig. 3 is a plan view of the top of the assembly of Fig. 2, showing the feed pipes and the pipes of the cooling and lubricating system, and

Fig. 4 is a plan view of the slurry and emergency water distribution plate taken on the line 4—4 of Fig. 2.

Referring to Fig. 1 it will be seen that the assembly indicated generally by reference numeral 1 consists of a drying chamber 2 having a furnace 3 superimposed thereon, both being enclosed by a cylindrical side wall 4. Supporting beams 5 carrying a central well structure 6 are mounted on the top of this wall, as by vertical beams 7. In the embodiment shown the furnace 3 is formed within the top portion 12 of the side wall 4 by an insulated ceiling 13, which is suspended from the supporting beams 5 by rods 14 and hangers 15, and an imperforate heat-radiating metal partition 16 which constitutes a floor for the furnace and a horizontal ceiling for the spray drying chamber. This metal partition serves the important function of radiating heat from the furnace into the particles of material in the upper portion of the spray drying chamber while preventing the uncontrolled admixture of additional quantities of hot gases therewith, which increases the drying capacity of the apparatus and aids in forming a spray-dried material of controlled shape and particle size.

The partition 16 is made up of a set of metal plates laid on an equal number of radial beams 18 which are supported at their outer ends by the side wall 4. At their inner ends these beams are joined as at 20 to a

2

vertical annular baffle 21, which is spaced outwardly from the central well 6 and forms therewith an annular passage 22. The baffle 21 and the inner ends of the beams 18 are supported by a ring of insulated rods 23 which extend through the ceiling of the furnace and are hung from the supporting beams 5. Near its lower edge, and preferably below the level of the beams 18, the baffle is inclined inwardly at 24 to form a restricted portion in which a set of inclined gas-directing vanes 26 is mounted.

Set in the outer wall 12 of the furnace are a number of burner tunnels 27, each enclosing a gas burner 28. These tunnels and burners are set at an angle between the radius and the tangent to the wall of the furnace, so that the flames from the burners travel through a spiral path. It will be noted that the burners are mounted relatively close to the metal floor 16, so that this floor soon becomes very hot and radiates a substantial proportion of the heat from the burners directly into the drying space below. The products of combustion, at the end of their spiral path around the furnace, pass upwardly over the vertical baffle 21 and downwardly through the space 22, being deflected by the vanes 26 into a vertically rotating path.

The drying capacity of the apparatus of the present invention is such that a motor can be used having a greater power output than any heretofore employed for this purpose. Such a motor is shown on Fig. 2 of the drawings. While this motor, per se, is more or less conventional in design and is not a part of the present invention, its cooling system and the structure and location of the slurry feed and emergency water distribution pipes, and particularly the distribution plate whereby these are connected with the spray wheel 30, constitute important novel features of the invention.

Referring to Fig. 2, the spray machine indicated generally by reference numeral 35 comprises a rotor 36 and a suitable stator 37, both mounted within a water jacketed enclosure 38. The upper and lower bearings 39 and 40 of the rotor shaft 41 are designed for operation at high speeds and are supplied with a spray of oil through pipes 42 and 43 respectively. These bearings are mounted in upper and lower plates 45 and 46, a plan view of the upper plate 45 being shown in Fig. 3 of the drawings. Air ducts 47 and 48 are provided in the enclosure 38, through which air is forced to aid in cooling the motor. One of these air pipes is shown at 49 on Fig. 2, the air being admitted through port 50 and passing over the field 51, through the stator 37 and out through openings 52 in the upper plate 45. The machine illustrated is a two pole, 3 phase, 150 H. P., 210 cycle motor operated with a frequency generator unit which can vary the frequency up to 260 cycles or down to 158 cycles, thus giving any desired speed to the rotor shaft 41 between 9500 and 15,600 revolutions per minute.

The motor is enclosed by a water jacket 55 having a flat bottom 56 which forms with the lower plate 46 a water passage that surrounds and cools the lower bearings 40. Water inlet and outlet pipes 57 and 58 permit a continuous circulation of water through this jacket, thus protecting the motor from the heat of the furnace in which it operates. Slurry pipes 59, 60 and 61 also pass through the cooling jacket 55 in order to avoid the danger of clogging by premature heating and solidification of the solutions or slurries to be spray dried. These pipes extend through the bottom 56 of the cooling jacket and communicate with the distributor 62, which feeds the materials to be dried to the spray wheel 30.

The distributor 62 is made up of a lower body portion 63 and a cover plate 64 carrying a central annular shield 65, the body portion and cover plate being fastened together and to the cooling jacket by bolts 66. As is shown in Fig. 4 of the drawings the body portion 63 consists of a flat circular plate 67 having a machined outer edge 68 and a set of slurry channels 69, 70 and 71 aligned at their outer ends with slurry pipes 59, 60 and 61 respectively and having a downwardly turned lip, as at 72, at their inner ends. Corresponding openings in the cover plate, as at 73, permit the solution

or slurry to be dried to flow through the channels and discharge over the lip 72 onto the spray wheel, which is of a conventional type, from which it is thrown outwardly in the form of fine droplets into the drying chamber 2.

It is very important to maintain a constant flow of liquid through the apparatus at all times when the furnace 3 is in operation as otherwise the spray wheel 30 and probably other parts of spray drier would be damaged by the hot furnace gases. Provision is therefore made to discharge a stream of water on the spray wheel if the slurry pipes should become clogged or if the regular feed of slurry should be interrupted for any other reason. For this purpose an emergency water pipe 75 (Fig. 3) is located above and in communication with a water channel 76 in the body portion 63 of the distributor. This water channel has a dam 77 across its inner end to prevent the channel from becoming clogged by hardened slurry during normal operation. Preferably the flow of water in the pipe 75 is controlled by a valve that is cross-connected to the slurry feed so that the water valve will open automatically when the flow of slurry is interrupted.

The spray machine 35 is adapted to fit closely within a vertical cylinder 80 in the central well structure 6, and is provided with an outer flange 81 which rests on an inner shoulder 82 in the cylinder 80 when the motor spray wheel are in operative position. The feed slurry, cooling water, compressed air, oil and emergency water are supplied to the inlet pipes shown on Fig. 3 of the drawings by suitable flexible connections, which are not shown, so that the spray machine 35 can be raised through the cylinder 80 and removed for cleaning or repairs at any time. Electric current is also supplied to the motor by a flexible cable, which is not shown, and a suitable thermocouple well may also be provided if desired. The central cylinder 80 is braced against vibration by a set of brackets 83 which span the annular space 84 between the inner cylinder 80 and the outer, insulated cylinder 85 of the central well structure 6. It will thus be seen that the spray machine is protected from the heat of the furnace, first by a layer of insulation 86 on the inner wall of the furnace, then by the air space 84, then by the water in the cooling jacket 55, and then by the cooling air.

The operation of the apparatus is best shown by a specific example of results which have been obtained herein. A slurry of a hydrated silica-alumina catalyst, containing 87% of silica and 13% of alumina on the dry basis and prepared by suspending in water a precipitated, filtered and washed silica-alumina produced as described in the patent of K. D. Ashley and A. O. Jaeger, No. 2,478,519, dated August 9, 1949, was sup-

plied at a solids content of about 6.8-8.0%. Natural gas was used as fuel in the furnace 3, which furnace contained 6 gas burners each having a capacity of 6,000,000 B. t. u. per hour. The gas flow was estimated at 2380 lbs. per minute, based on the heat balance. The outlet gas temperature in the pipe 11 was 250° F. The following operating results were obtained when a 9-inch diameter, 45° V-type spray wheel was used.

This is a division of my copending application Serial No. 105,943 filed July 21, 1949, now Patent 2,644,516.

What I claim is:

In a spray drier, a spray machine comprising a motor having a vertical rotor shaft, a spray wheel attached to the lower end of said shaft, a distributor between said motor and said spray wheel containing a plurality of feed channels adapted to supply liquid material to be spray-dried to said wheel and also containing an emergency water channel having a dam to prevent clogging by material from said feed channels, a water jacket surrounding said motor and slurry pipes and an emergency water pipe extending through said water jacket and communicating with said feed channels.
